Primary Examiner—Daniel D Bui(74) *Attorney, Agent, or Firm*—Melanie G. Gover(57) **CLAIM**

The ornamental design for a hermaphroditic electrical connector, as shown and described.

DESCRIPTION

FIG. 1 is a perspective view of a hermaphroditic electrical connector showing our new design;

FIG. 2 is a right side view thereof;

FIG. 3 is a top side view thereof;

FIG. 4 is a bottom side view thereof;

FIG. 5 is a left side view thereof;

FIG. 6 is a front side view thereof; and,

FIG. 7 is a back side view thereof.

The dash-dot line represents the boundary of the claimed design, the broken line showing of the environment is for illustrative purposes only and forms no part of the claimed design.
